UNITED STATES PATENT OFFICE.

LOUIS HOEN, OF UTICA, NEW YORK.

GRATE.

1,187,735.

Specification of Letters Patent. Patented June 20, 1916.

Application filed October 22, 1915. Serial No. 57,375.

To all whom it may concern:

Be it known that I, LOUIS HOEN, a citizen of the United States, residing at Utica, in the county of Oneida and State of New York, have invented certain new and useful Improvements in Grates, of which the following is a specification, reference being had therein to the accompanying drawing.

My invention relates to a grate, and I declare the following to be a full, clear, concise and exact description thereof sufficient to enable any one skilled in the art to which it appertains to make and use the same, reference being had to the accompanying drawings in which like reference characters refer to like parts throughout the specification.

The object of the invention is to provide a simple efficient grate for use in furnaces, whereby the clinkers and ashes will be effectively separated from the coals in the fire pit and dumped into the ash pit of the furnace with but very little effort on the part of the operator or user. The grate is also designed to provide a substantial bed for the coals or fuel and yet increase the interstices, particularly in the region of the periphery of the grate, whereby to provide for a greater amount of air space with the resultant advantage in the consumption of the fuel. Furthermore, the parts of the grate are few in number and can be easily assembled, so that worn or broken parts can be readily replaced by new ones.

These objects will appear by referring to the drawings in which:

Figure 1 is a plan view of the grate; Fig. 2 is a central vertical section taken on the line 2—2 of Fig. 1; Fig. 3 is a transverse vertical section taken on the line 3—3 of Fig. 1; Fig. 4 is a detail fragmentary view showing a vertical section on the line 4—4 of Fig. 1; Fig. 5 is a detail fragmentary view showing a vertical section taken on the line 5—5 of Fig. 1; Fig. 6 is a detail fragmentary view, showing a vertical section on the line 6—6 of Fig. 2.

Referring more particularly to the drawings, the grate embodies a frame —1—, which comprises an annular ring 2, having

the peripheral teeth 3 and the center bar 4. 50 The annular ring 2 and the peripheral teeth 3 are each provided with the pyramidal teeth 5 adapted to aid in loosening the clinkers and ashes when the grate is in motion. The center bar 4 has disposed at its 55 middle portion, a depending gudgeon 6 resting in the loose bearing 7 formed in the bracket portion 8 of the bilateral arm 9 of the yoke 10. The rear ends of the arm 9 are formed integral with the rear hanger 60 bar 12 having the trunnions 13 and 14 adapted to be mounted in corresponding bearings, not shown, in the furnace. The yoke 10 has formed also integral therewith, the two parallel disposed bars 15—15 65 developing at their forward ends into the lateral branching arms 16—16, whose extremities detachably engage certain well known hanger bars employed in nearly all furnaces, whereby to hold the grate in elevated position within the fire pot. The rear hanger bar 12 is furnished with two integral upstanding posts 17—17 having recesses with open bearings 18—18 for mounting the trunnions of the rollers 19—19 which 70 support in an antifriction manner the annular ring 2 of the frame —1— at different locations. The forward part of the frame —1— is provided with an extension 20 having on its under surface a rack or strap gear 21 adapted to mesh with the spur gear 22 mounted with a key 60 to revolve with the shaker shaft 23. The gear 22 is held in given longitudinal position upon the shaker shaft 23 by reason of its tapering aperture or hub through which projects the corresponding portion 24 of the shaft 23 and by the horseshoe or U shaped gear shield 25 disposed between the spur gear 22 and the collar 26 integral with the shaker shaft 23. The free ends of the U shaped gear shield 25 are provided with the caps or lugs 27—27 75 having suitable apertures for the disposition of the cotter pin 28. The collar 26 is cut away on a straight line at 29 to make way for the adjacent surface of the cotter pin 28, when assembled, whereby to give 80 the said cotter pin 28 a better purchase for 85

90

95

compelling the U shaped gear shield 25 to revolve with the shaft 23.

The outer end of the shaft 23 is angled as at 30 for the detachable connection of a 5 crank handle, whereby to turn the shaft 23. The opposite or inner end of the shaft 23 has a rotary bearing at 31 in the bracket portion 8 of the yoke 10. The shaft 23 is prevented from moving longitudinally by the collars 10 32—32 which are formed integral with the shaft 23 and lie on either side of the bearing formed by the cross bar 33 connecting the parallel bars 15 of the yoke 10 and the cap bar 34 held to the cross bar 33 by the 15 screws or bolts 35—35.

The annular ring 2 is provided at suitable intervals with apertures or bearings for the reception of the trunnions 36 and 45 of the right and left short bars 37 and 20 38 respectively and the right and left long bars 39 and 40 respectively. The bars 37, 38, 39 and 40 possess the laterally projecting teeth 41 disposed at given intervals therealong with the resultant interstices therebetween, whereby to form a kind of lattice work as a bed for holding the fuel while burning. The under surface of the ends of the teeth 41 are rounded off, whereby to aid in pushing the unburnt coals back and to 25 crush and push below the clinkers, when the adjacent teeth 41 are passing each other, as the bars 37, 38, 39 and 40 are revolved.

The forward journals 45 of the bars 37, 38, 39 and 40 are held in their open bearings in the annular ring 2 by the cap plates 46 and 47, which have formed therein the counter parts to the open bearings in the annular ring 2. The cap plates 46 and 47 are fastened in assembled position by the 40 bolts or screws 48.

A depending lever 50 is formed integral with each of the bars 37, 38, 39 and 40. The lower end of these levers 50 rest in recesses of a T shaped fulcrum bar 51 and are held 45 therein with a limited amount of motion by the cotter pins 52. The rear end of the T-shaped fulcrum bar 51 is provided with an elongated recess 53, up through which projects a gudgeon or axle bar 54 integral 50 with the peninsular portion 55 of the rear hanger bar 12.

The grate may be operated by engaging the end 30 of the shaker shaft 23 with any ordinary crank handle and then turning 55 the same, first in one direction and then the other, whereupon the spur gear 22 will be revolved to thereby cause its intermeshing rack 21 to be oscillated in a horizontal plane. The actuation of the rack effects a reciprocal 60 rotary movement of the frame —1— and of its connected parts the bars 37, 38, 39 and 40. Simultaneously with the rotary movement of the frame —1—, the bars 37, 38, 39 and 40 will be rocked axially because

of their connection by means of the levers 50 65 with the fulcrum bar 51 that is adapted to move a short distance forward and upward slightly to conform to the revolving motion of the said bars about the depending gudgeon 6 as an axis.

It will, therefore, be apparent that the bars 37, 38, 39 and 40 are subjected simultaneously to a planetary or compound motion comprising that of a revolution on their own axes 36 and 45 respectively, and about 70 the gudgeon 6 as an axis. This planetary motion is highly efficient in rendering the grate effective for the purpose of dumping the ashes and grinding the clinkers from the surface thereof. Furthermore, the leverage provided by the long arms 50 secures a sufficient amount of revolution of the bars 37, 38, 39 and 40 upon their own axes with a minimum amount of power for actuating 75 the same. The pyramidal teeth 5 will aid materially in loosening the ashes and the rounded under surfaces of the teeth 41 will aid in pushing back the fuel and grinding the clinkers. Moreover, the peripheral teeth 3 of the annular ring 2 will cause the 80 ashes and clinkers to be cleaned from the outside circumference of the grate as well as from the contiguous surface of the fire pot of the furnace. And still further, the peripheral teeth 3 provide interstices or air 85 spaces at the extreme circumference of the grate for the circulation of the air at that portion, whereby to cause a more equal distribution of the air over the under surface of the fuel with the resultant increase of 90 consumption and consequent intensity of heat.

Although I do not consider it necessary, a headed screw 62 and a washer 63 may be employed to retain the gudgeon 6 within 105 its bearing.

Having thus described my invention, what I claim as new and desire to secure by Letters Patent is:

1. In a grate, a frame, a yoke supporting 110 said frame, a rack formed in said frame, a gear in mesh with said rack, whereby to oscillate said frame, a gudgeon depending from said frame, a bracket having a bearing for said gudgeon, rotary bars mounted in 115 said frame, levers depending from said bars, and a T shaped fulcrum bar engaging said levers, whereby to rock said bars when said frame is oscillated.

2. In a grate, a frame, a yoke supporting 120 said frame, a rack formed in said frame, a gear in mesh with said rack, whereby to oscillate said frame, a gudgeon depending from said frame, a bracket having a bearing for said gudgeon, posts formed in said yoke, rollers mounted in said posts for supporting said frame, rotary bars mounted in said frame, levers depending from said bars, and a 125

T shaped fulcrum bar engaging said levers, whereby to rock said bars when said frame is oscillated.

3. In a grate, a frame, a yoke supporting said frame, a rack formed in said frame, a gear in mesh with said rack, whereby to oscillate said frame, rotary bars mounted in said frame, levers depending from said bars, and a T shaped fulcrum bar engaging said

levers, whereby to rock said bars when said frame is oscillated.

In testimony whereof I have affixed my signature in the presence of two witnesses.

LOUIS HOEN.
